UNITED STATES PATENT OFFICE.

EDWIN LANE, OF JOHNSTOWN, PENNSYLVANIA.

RAIL JOINT OR CHAIR.

SPECIFICATION forming part of Letters Patent No. 658,528, dated September 25, 1900.

Application filed July 20, 1900. Serial No. 24,296. (No model.)

To all whom it may concern:

Be it known that I, EDWIN LANE, a citizen of the United States, residing at Johnstown, in the county of Cambria and State of Pennsylvania, have invented new and useful Improvements in Rail Joints or Chairs, of which the following is a specification.

This invention relates to certain new and useful improvements in rail-joints or railway-chairs.

The object of my invention is to provide an improved chair or joint for connecting the adjacent ends of railway-rails and supporting them between the ties, the construction of the chair or joint being such that the rail may be readily removed from the chair without separating the same from the ties, the construction being such that provision is made for lateral expansion and contraction without causing undue strain upon the connecting-bolts.

My invention consists in the construction and arrangements of the parts, which includes a bar for retaining one of the fish-plates to the base-plate of the chair, the fish-plate which said bar overlies having slots, which will permit a movement of one of the fish-plates and the base-plate, especially laterally; so that expansion will not tend to loosen the base-plate from the ties.

In the accompanying drawings, Figure 1 is a vertical section taken through a railway joint or chair constructed in accord and with my improvements. Figs. 2 and 3 are perspective views of the fish-plates, showing the same upon the base; and Fig. 4 is a perspective view of the base-plate and bar for holding the outer fish-plate in engagement therewith.

A refers to a base-plate which is of sufficient length to span the space between two ties, and this base-plate has in its longitudinal edges recesses a , through which are passed spikes for connecting the base-plate to the tie. At suitable intervals one side of the base-plate is provided with countersunk openings a' for the passage of rivets and on the other side with similar openings a^2 for the passage of bolts. The base-plate is preferably made up from a piece of sheet metal and may be rolled or otherwise shaped so that it is normally slightly convex transversely on

its upper face, more particularly where it is engaged by the base-flange of the rail, and the convexity is sufficient to prevent sagging of this plate between the ties and at the same time allow a slight spring or give to the same during the passage of a train over the joint. This construction provides for the lateral expansion of the base-plate during the passage of a train and prevents said base-plate sagging, which would have a tendency to loosen or withdraw the spikes, whereas the convexity causes the plate merely to bear against the spikes during the passage of a train.

A base-plate constructed as above described may be considered as a permanent fixture on the way or ties, and in driving the spikes which secure the base-plate to the tie there should be allowance made for lateral expansion, the heads of the spikes holding the base-plate upon the ties.

To the base-plate A, I attach, by means of rivets a' , a fish-plate B, and in use this fish-plate will engage the inner side of the rail. As the parts are connected to each other at the factory, they will be, to all intents and purposes, as if made in one piece, except that in practice the fish-plate or angle-iron B will be made of cast metal, while the base-plate is of rolled metal.

C refers to a second angle-iron or fish-plate, which is secured to the rail D in the usual manner by bolts b , and the outer edge of this fish-plate C is provided at intervals with open-ended slots or recesses c , through which pass bolts d , the heads of said bolts lying in the countersunk openings a^2 of the base-plate A. The bolts d are of sufficient length to extend considerably above the flange of the fish-plate C, and the open-ended recesses or slots c have their walls positioned at a considerable distance from the bolts, so that the parts may give without being brought in immediate contact with the bolt. The outer chair or joint bar is held in engagement with the base-plate by a bar E, which is shaped on its under side to overlie the flange of a fish-plate C and contact with the base-plate. In order to provide for such construction and a flat bearing for the nuts of the bolts d , the upper edge of the bar E is flat and its outer edge is at right an-

gles with the top, while its under side is at an angle and has a depending portion which bears upon the base-plate.

To separate the rail D from the chair or joint, it is only necessary to remove the usual connecting-bolts *b* and the nuts of the bolts *d*, which will permit the removal, first, of the bar E and then of the fish-plate C, which permits the removal of the rail, so that it can be replaced by another one without getting the parts out of alinement. It will also be noted that the connection of the fish-plate C with the base-plate A is such that there may be a slight lateral movement without undue strain upon the connecting means.

Having thus described my invention, what I claim as new is—

1. In a rail-joint, a base-plate shaped so as to be normally convex transversely, a fish-plate rigidly secured by connecting means to the base-plate, in combination with a second fish-plate having open-ended slots, a bar which is adapted to rest upon said second fish-plate and is connected to the base-plate

by bolts which pass through the open-ended slots, substantially as shown and for the purpose set forth.

2. In a rail-joint, the combination with a base-plate to which an inner fish-plate is permanently attached, of an outer fish-plate having at its edge open-ended slots, a bar adapted to overlie longitudinally the edge and a portion of the top of the outer fish-plate and when in such engagement to bear upon the base-plate said bar having apertures which register with the open-ended slots of the outer fish-plate, and bolts which pass upwardly through the base-plate the open-ended slots and the apertures in the bar, substantially as shown.

In testimony whereof I have hereunto set my hand in presence of two subscribing witnesses.

EDWIN LANE.
